ATTORNEY.

UNITED STATES PATENT OFFICE

2,393,410

HOLLOW HYDRAULIC JACK

William S. Pine, Southgate, Calif.

Application September 22, 1942, Serial No. 459,256

2 Claims. (Cl. 309—34)

My invention relates to a hydraulic jack and particularly to a jack of this class for drawing two or more members relative to each other.

An important object of this invention is to provide a simple and efficient hydraulic jack which will serve as an ordinary jack for raising objects above and also upwardly from below the jack; and which will also serve for drawing two or more members together, or for withdrawing one member from another, as is done in arbor press operation.

Another important object of this invention is to provide a compact hydraulic jack of this class having a base cylinder and a plunger or raising member adapted to be projected thereabove, and in which the upper portion of the cylinder serves as the reservoir and a corresponding and aligned cylinder portion below serves as the compression chamber for the raising liquid.

A further object of this invention is to provide simple and efficient means for transferring the liquid from the reservoir into the compression chamber.

An important object of this invention, also, is to provide a novel and efficient method of constructing and finishing the adjacent surfaces of two concentric cylinders for a jack of this class, and in which there is provided a narrow annular cylindrical space of considerable depth therebetween.

A further important object of this invention is to provide novel, simple and economical means of variously sealing the liquid of the hydraulic jack against escape, and to provide especially tight joints between mutually reciprocating cylindrical parts to withstand unusually high fluid pressure, and provide novel and effective means of securing the sealing means in place.

With these and other objects in view, as will appear hereinafter, I have devised a hydraulic jack of this class having certain novel features of construction, combination and arrangement of parts and portions, as will be hereinafter described in detail, and particularly set forth in the appended claims, reference being had to the accompanying drawing and to the characters of reference thereon, which form a part of this application, in which:

Fig. 1 is a top view of my hydraulic jack in a preferred form, portions thereof being broken away to facilitate the illustration;

Fig. 2 is a fragmentary side elevation thereof, also showing portions broken away and in section, the sectional portion being taken through 2—2 of Fig. 1;

Fig. 3 is a sectional elevation thereof taken through 3—3 of Fig. 1;

Fig. 4 is an enlarged fragmentary sectional view showing the sealing means between the plunger and the cap of the cylinder;

Fig. 5 is an other enlarged fragmentary slightly exploded sectional view showing particularly the means for forcing the sealing leather against the wall of a relatively movable member; and

Fig. 6 is an end view of the head of the pump plunger taken through 6—6 of Fig. 3.

The enclosing housing of my hydraulic jack consists of an outer cylinder 1, an inner concentric cylinder 2, and a thick head 3 connecting the lower ends of said cylinders, which head forms the base of the jack. The space between the cylinders 1 and 2 provides a relatively narrow annular compartment or annular cylindrical space A into which extends the lower portion of the moving or extensible member of my jack, which is the plunger. This moving member consists of an annular piston 4 which has at its radially inner portion an upwardly extending tubular piston rod or shank 5. The upper end of the tubular piston rod portion has an axial opening 5^a which is smaller in diameter than the main portion of the piston rod, forming a shoulder 5^b which is adapted to engage the upper end of the inner cylinder 2 for limiting the lower position of the piston. The diameter of the opening 5^a is substantially the same as the inside diameter of the inner cylinder 2. The upper end of the space between the outer cylinder 1 and the tubular piston rod is enclosed by a cap 6 which is screwed over the upper end of the outer cylinder.

The main enclosure member of my jack, consisting of the cylinders 1 and 2 and the base 3, is made by forming the cylinder 1 and the base 3 as one member, machining the inner cylindrical wall of the cylinder 1, machining the exterior surface of a tubular member to form the cylinder 2, and then welding or otherwise securing the lower end of the cylinder 2 into a corresponding hole in the base 3, as indicated by B in Fig. 3.

The piston rod 5 and the piston 4 fit loosely in the space A, and the tubular piston rod extends loosely through the axial portion of the cap 6. There are, however, provided means in connection with the piston and cylinders, means for sealing the respective joints between said members.

At the lower end or face of the piston is secured a sealing leather 7 which is of inverted U-shaped cross-section, the outer leg or flange 7^a engaging

the inner wall of the outer cylinder while the inner leg or flange 7^b engages the outer surface of the inner cylinder. This sealing leather is secured in place by an annular retaining ring or plate 8 located within the hollow portion of the sealing leather, the annular retaining ring being secured to the lower face of the piston by screws 9 .

In a cupped sealing leather of this type, the outer flange 7^a normally engages tightly the inner surface of the outer cylinder. I have provided, however, a flexible and elastic annular member 10 which is seated within an annular groove 8^a , this groove being provided in the bore of the retaining member. The central opening of the flexible member 10 is bevelled at the upper portion and this bevelled portion engages the correspondingly bevelled lower edge of the cup or sealing leather 7 . As the retaining member 8 is clamped in position, the elastic member 10 forces the inner flange of the cup leather against the outer face of the inner cylinder 2 by reason of the mutually engaging bevelled surfaces of the sealing and the elastic ring. As the retaining member is clamped to position the elasticity of the member 10 also serves resiliently to force the lower portion of the flange 7^b against the outer surface of the inner cylinder. In this manner the liquid in the compression space or chamber A^1 below the piston is prevented from escaping upwardly past the cylinder walls.

The portion of the space A above the piston, designated A^2 , is the reservoir for the liquid for motivating the jack. In the cap 6 is provided a sealing ring 11 for preventing escape of the liquid from the reservoir A^2 , particularly when the jack is used in any other than an upright position. This ring is also of inverted U-shaped cross-section, the outer leg 11^a being positioned at the bottom of a groove 6^a , in the wall of the bore of the cap, and the outer side of the other leg 11^b being positioned in engagement with the outer cylindrical surface of the piston rod 5 . The inner leg 11^b terminates in a feather edge and is resiliently forced against the piston rod, the dotted lines in Fig. 4 indicating the normal shape of the inner leg of the sealing ring before engaging the piston rod.

The fluid of my jack is transferred from the reservoir A^2 into the compression chamber A^1 by a pump mechanism placed preferably at the side of the outer cylinder 1 . This pump mechanism consists essentially of a cylinder 21 and a plunger 22 . The cylinder is shown as screwed at its lower end into a fitting 23 and the fitting 23 is secured at its lower end in a threaded recess 24^a of a base 24 secured to and forming substantially a lateral extension of the base 3 of the jack. At the upper end of and around the plunger 22 is provided a stuffing box 25 . The plunger is provided with an enlarged bifurcated head 22^a which is pivotally connected to the intermediate portion of an operating lever 26 . The end of the operating lever is pivotally connected by a link 27 to a boss 24^b on the base 24 .

At the exterior of the outer cylinder is provided a conduit 28 which may be made as a part of the outer cylinder 1 . This conduit is connected at its upper end, by means of a port 28^a , with the upper portion of the reservoir. The lower end of the conduit 28 is connected by means of a transverse port 24^c with an annular channel at the lower and peripheral portion of the threaded plug of the fitting 23 , the channel being formed by a groove 23^a at the lower end of the fitting. The fitting 23 is provided with two longitudinal

passages 23^b and 23^c , the former being positioned at the side of the fitting and extending from said annular channel to the upper end of the fitting or to the threaded recess receiving the lower end of the cylinder 21 ; the other passage 23^c extends axially through the fitting from the lower end of the cylinder 21 to the lower end of the fitting. In these passages are provided ball check valves 29 and 30 , respectively, the former allowing fluid to pass into the cylinder 21 and the latter preventing a return of fluid into the cylinder. The lower end of the passage 23^c communicates with a transverse passage 3^a which communicates with the lower end of the annular compression chamber A^1 through a port in the base 3 . In this manner fluid is forcefully transferred from the reservoir to the compression chamber.

The interior of the outer cylinder 1 is also connected with the conduit 28 by means of a small by-pass orifice 28^b , this orifice being positioned below the port 28^a so as to prevent the lower end of the sealing leather 7 to be forced outwardly beyond the orifice 28^b .

At the juncture of the conduit 28 and the horizontal passage 24^c is provided a thimble screen 31 which may be inserted through an opening normally closed by a plug 32 . At the lower end of the intake passage 23^b is also provided a screen 33 .

In order to relieve the pressure within the compression chamber A^1 and allow the liquid again to be transferred to the reservoir A^2 , I have provided a release valve which consists of a ball 41 and a release screw 42 . The ball 41 , when it is desired to prevent the return of fluid, is seated over a passage 24^d which communicates with the passage 3^a . This ball is located in an enlarged bore 24^e at the outer end of which is provided a gland 43 through which the release screw 42 extends. The bore 24^e is connected with the annular passage provided by the channel 23^a by means of an angular port 24^f , as shown in Fig. 1. Thus, the liquid in the compression chamber of the jack is returned to the reservoir through the passages 3^a , 24^d , 24^e , 24^f , 23^a , 24^c , conduit 28 and port 28^a .

To facilitate the return of the piston to its lowered position, I have provided a compression coil spring 51 within the reservoir A^2 , its ends engaging the cap 6 and the piston 4 .

My jack is constructed for drawing two members together or for raising objects from below the jack. For this reason, the inside diameter of the inner cylinder is relatively large, and the axial opening 5^a , at the upper end of the piston rod, is correspondingly large. To raise an object from below the jack, a rod 61 may be placed through the axial portion of the jack and the upper end may be supported by a supporting disc 62 , or the like, on the upper end of the piston rod, as shown in Fig. 3.

Though I have shown and described a particular construction, combination and arrangement of parts and portions, I do not wish to be limited to the same, but desire to include in the scope of my invention the construction, combination, and arrangement substantially as set forth in the appended claims.

I claim:

1. A machine of the class described, a cylinder, a piston reciprocally mounted therein, a sealing leather member having a flange positioned against the face of the piston head and a second flange engaging the cylinder wall, the edge of the second flange being bevelled towards the first

flange, an annular plate securing the first flange to the piston, said plate being provided in its side wall with an annular groove, and a flexible annular member mounted with a portion in the groove and extending with its other beyond the plate, the outer portion of the flexible member being bevelled and engaging the bevelled outer edge of the second flange for forcing said flange against the wall of the cylinder, said flexible annular member being positioned radially outwardly from the second flange for resiliently contracting the diameter of the second flange around the wall of the cylinder.

2. A machine of the class described, a cylinder, a piston reciprocally mounted therein, a sealing leather member having a flange positioned against the face of the piston head and a second

flange engaging the cylinder wall, the edge of the second flange being bevelled towards the first flange, an annular plate securing the first flange to the piston, said plate being provided in its side wall with an annular groove, and an elastic annular member mounted with a portion in the groove and extending with its other portion beyond the plate, the outer portion of the elastic member being bevelled and engaging the bevelled outer edge of the second flange for forcing said flange against the wall of the cylinder, said elastic annular member being positioned radially outwardly from the second flange for resiliently contracting the diameter of the second flange around the wall of the cylinder.
